DESIGN.

W. GORMAN.
Door-Knobs.

No. 7,020.

Patented Dec. 9, 1873.

FIG.1.

FIG.2.

WITNESSES.INVENTOR.

UNITED STATES PATENT OFFICE.

WILLIAM GORMAN, OF NEW BRITAIN, CONNECTICUT, ASSIGNOR TO THE RUSSELL AND ERWIN MANUFACTURING COMPANY, OF SAME PLACE.

DESIGN FOR DOOR-KNOBS.

Specification forming part of Design No. 7,020, dated December 9, 1873; application filed November 15, 1873.
[Term of Patent 14 years.]

To all whom it may concern:

Be it known that I, WILLIAM GORMAN, of New Britain, in the county of Hartford and State of Connecticut, have invented a new Design for a Door-Knob; and I do hereby declare that the following specification, taken in connection with the drawing, is a full, clear, and exact description thereof.

Figure 1 is a front view. Fig. 2 is a side view of said design and door-knob.

The principal features of my design consist of a rosette, A, in the center of the knob, and a number of radial Gothic borders or frames, B, surrounding said rosette within a plain concentric border, E, at the margin. The rosette A may be composed of a number of plain radial figures, e, from a button center, d, a plain border, f, a concentric row of spots, i, and a plain border, l, at the outside boundary of the rosette, as shown in the drawing. But this

arrangement of ornamental figures is not essential, and the rosette may be differently constituted without departing from my said design. So also the Gothic frame-work B may be filled with cinque-foils F, or composite figures of leaf-work or scrolls, or other similar ornamental figures G. But these may be changed or omitted without affecting the said design, the distinguishing features of which are the rosette A and the Gothic frame-work B in combination.

What I claim as my invention, and desire to secure by Letters Patent, is—

The design for a door-knob, substantially as herein shown and described.

WILLIAM GORMAN.
